ANTISLIPPING DEVICE FOR SHOES

Leo V. Russo, Chicago, Ill.

Application September 6, 1952, Serial No. 308,267

3 Claims. (Cl. 36—7.6)

1

This invention relates to improvements in anti-slipping devices for attachment to shoes, particularly, to a device capable of easy yet secure attachment to and over the heels and soles of shoes whereby the equipped shoes may be advantageously worn for and when the wearer is sports participating, as when playing golf.

It is an object of the invention to provide a shoe heel and sole attachable anti-slipping device which may be attached to those types of shoes normally used for street or casual wear without alteration or modification thereof, or mutilation or damage thereto, and when desired, can be removed, thus returning the shoe or shoes to original street wear form.

It is also an object of the invention to provide a device of the stated character adjustable in shape and size, permitting its satisfactory adaptation to and use on shoes of different sizes (both length and width), and to an extent, form contours and shapes.

Another object of the invention is to provide the anti-slipping attachment with a novel and efficient form of calk, easily and readily connectible to and with the shoe heel and sole engaging bodies thereof and entirely capable of remaining firm and nonmovable with relation thereto, whereby to ensure a maximum of gripping engagement with a tread surface, such, for example, as the earth, sod, etc., of a golf course.

A still further object of the invention is to provide a calk, as above, so constructed as to serve a dual function; first, as an anti-slipping means or device per se, and second, as a means for firmly and securely interconnecting the co-operable body constituting members or portions of the attachment in their particularly preadjusted relations, i. e., relationships effected according to the shapes and sizes of the heels or soles of shoes to which the anti-slipping device is attached.

A further and important object of the invention is to provide a shoe adaptable anti-slipping device of simple yet durable construction, capable of shape and size variation with but a minimum of effort, of being securely adapted to and over the heels and soles of shoes, and quite importantly, capable of being produced or manufactured at a comparatively low cost, rendering the same especially attractive to and advantageous for use by persons wishing to convert casual or street wear shoes into sport types of shoes.

The foregoing, as well as other objects, advantages and meritorious teachings of my invention, will be in part obvious and in part pointed out

2

in the following detailed disclosure thereof, when taken in conjunction with the accompanying drawings, it being understood that the form of the invention presented herein is precise and what is now considered to be the best mode of embodying its principles, but that modifications and changes may be made in specific embodiments without departing from its essential features.

10 In the drawings:

Figure 1 is a perspective view of my improved anti-slipping device, the heel securing strap being shown in dotted lines.

Figure 2 is a bottom plan view of the same.

Figure 3 is a top plan view thereof.

Figure 4 is a disassembled plan view of the primary component members of the device in blank form.

Figure 5 is a side elevation of the anti-slipping device with the heel securing strap shown in full lines and the interengaged portions of the heel and sole bodies of the devices shown in longitudinal section.

Figure 6 is a disassembled detail in perspective of the novel form of calk employed by the device, and

Figure 7 is an enlarged section taken on the line 7—7 of Figure 3, looking in the direction in which the arrows point, illustrating the manner in which one of the calks, such as shown in Figure 6, is engaged with and mounted on the device sole body and one of the adjustable sole clamp plates, securing the latter to the former.

Referring in detail to the accompanying drawings, it is first noted that the anti-slipping device of my invention is produced and normally used in pairs, one for the left foot shoe and the other for a right foot shoe. In said drawings, however, I have shown the invention embodied in but one anti-slipping device (for the left foot shoe). It will be understood that the construction is the same in the companionate device (for the right foot shoe).

The invention comprises, generally, a shoe sole engaging body 1, a heel engaging body 2, and sole adjustable clamp plates 3 and 4. Each thereof are, preferably, made of metal or composition sheet-like stock of suitable flexibility and strength.

The shoe sole engaging body 1, substantially flat throughout its area, is of more or less ovate form whereby to substantially correspond to the shape of an average or normal left shoe sole. 55 Integral with and extending longitudinally from

an intermediate portion of its rearward or inner end is a flat tongue 5, of rectangular form.

The sole body 1 is formed with a plurality of slots or ways 6, of corresponding widths and lengths, spaced one from the other and each in relatively different angular relationships, though generally disposed transversely of said body, as is well shown in the Figures 1 and 4 of the drawings. Another slot or way 6' is formed in and disposed obliquely of the tongue 5. Also, it is preferable that the tongue 5 shall be offset slightly above the sole body 1 by bending or otherwise forming it, as indicated at 5' (see Figure 5).

The heel engaging body 1 is of substantially elongated rectangular form, having an upstanding curved counter member or flange 7 preferably, though not necessarily, integral with its rearward and outer end, as is shown in Figures 1, 3, 4 and 5 of the drawings. The way 8, of length slightly greater than the width of the tongue 5 of the sole body 1, is formed in and transversely of the forward and inner end portion of the heel body, which said end portion is upwardly offset, as by bending, at 9.

The counter 7 of the heel body may and preferably does have slots or ways 10 formed therein adapted to receive an angle engaging and attaching strap 10' therethrough.

Immediately outwardly or rearwardly of the transverse way 8 and intermediately thereof, an obliquely disposed slot or way 11 is formed in the heel body. Preferably, it is of a length substantially corresponding to that of the way 6' in the sole body tongue 5 and is in opposed angular relation thereto (see Figure 4).

Other longitudinally related pairs of slots or ways 12 and 12', of corresponding lengths, are formed in the heel body rearwardly of the oblique way 11. As will be noted, these pairs of ways are obliquely disposed with relation to the longitudinal axis of said body and those of the pair 12 are in opposed angular relation to those of the pair 12'.

The sole clamp plates 3 and 4 are adapted to be flatly engaged over and with the normally outer or under side of the sole body 1 and to be so related thereto as to permit of their general transverse and longitudinal placement adjustment theron.

The plate 3 is of generally ovate form having its outer side edge curved in a manner to substantially correspond to the curvature of the adjacent side edge of the sole body. A shoe sole engaging clamp or jaw 13 is integral with this curved outer side of the plate in proximity to its forward end and, obviously, is for securing engagement with and over the adjacent edge portion of a shoe sole to which the device is attached.

Relatively spaced angularly disposed ways 14 are formed in and extend, generally, longitudinally of the clamp plate 3.

The sole clamp plate 4 is of arcuate formation and length substantially corresponding to the sole body 1, less its tongue 5. A shoe sole clamp 15, similar to the clamp 13, is integral with the curved outer side edge of the plate in proximity to its forward end, which said outer side edge substantially corresponds in curvature to that of the curved adjacent side edge of the sole body.

Spaced angularly disposed ways 16 are formed in and disposed, generally, longitudinally of the clamp plate 4.

Because of the generally longitudinal disposition of said ways 14 and 16 in their respec-

tive clamp plates 3 and 4, it will be observed, upon reference to Figures 3 and 4, that they and each of them are arranged at angles with relation to the ways 6 in the sole body 1, i. e., at or from substantially right angles to angles of more acute degrees; also, that the total number of ways 14 and 16 in the plates 3 and 4, respectively, correspond to the total number of ways 6 in the sole body and that the former are individually adjacent the individual ways 6 in said sole body when the clamp plates are in their assembled relationships (see Figure 3).

In order that the clamp plates 3 and 4 may be immovably secured in pre-selected positions on the sole body 1, bolt calks of that form such as shown in Figures 6 and 7 of the drawings, are used. Since said calks are of the same construction, but one thereof will be described, it being understood that the description (to follow) will suffice for all thereof.

The bolt comprises a body or shank 17 (circular in cross-section) flatly and rather thinly headed, as at 18, and tapered and sharpened on its opposite and normally lower end, at 19, whereby to function as an efficient surface engaging and anti-slipping device. The upper or medial portion of the shank is screw-threaded, as at 20, and adapted to have a flat circular nut 21 turned thereonto. Said nut, preferably, has openings 22 in its normally outer side arranged for engagement by the usual fingers of a suitable form of spanner wrench or like tool, not shown. For obvious purposes, the bolt head 18 and the nut 21 are of substantially corresponding form and size, being sufficiently large to ensure firm and secure contact with objects to be engaged thereby or therebetween; also, thin though strong, to occupy a minimum of space.

In use of my improved anti-slipping device, 40 the sole and heel bodies 1 and 2 are assembled by engagement of the sole body tongue 5 in and through the way 9 of the heel body 2 in the manner well shown in the drawings. Thus engaged, the sole and heel bodies are secured in preselected or adjusted relationship by passing a bolt calk, such as above described, through the registering though oppositely obliqued ways 6' and 11 in the adjacent sole and heel body portions; thereupon, engaging a nut 21 with and over its screw-threaded portion 20 whereby to clampingly engage with and on the adjacent side of the heel body 2. The downwardly extended sharpened portion 19 of the bolt shank 17 will serve as an effectual anti-slipping device. However, should it be desired, this particular bolt may be formed with a comparatively shorter shank and without the sharpened and extended lower end.

The opposed oblique positioning of the ways 6' and 11 in the interengaged or overlapping portions of the sole and heel bodies is such that by moving said bodies toward or from each other, the overall length of the device may be decreased or increased; moreover, the lateral relative positioning of the sole body with relation to the heel body, and vice versa, may be selectively varied or adjusted, this, of course, prior to the tightening of the nut 21.

The clamp plates 3 and 4 are now placed flatly on the normally lower or under side of the sole body 1 in the manner indicated in Figure 2 of the drawings. Thus positioned, it will be noted that the generally longitudinally disposed ways 14 and 16 of said clamp plates will be in registration with the ways 6 formed in the ad-

jacent or overlying portions of the sole body 1. Bolt calks, as above described, are now passed downwardly or outwardly through the various registering ways in the clamp plates and the sole body, with the heads of such bolts bearing on adjacent portions of the sole body. Nuts 21 are turned onto the lower and extended sharpened shank portions of the bolts and inwardly into clamping engagement with the adjacent portions of the clamp plates and the sole body, in the manner clearly shown in Figure 7 of the drawings.

The clamp plates 3 and 4 may be selectively adjusted to predetermined portions of or on the sole body 1—either longitudinally or transversely thereof due to the generally transverse dis-positioning of the ways 6 in the sole body 1 and the generally longitudinal dis-positioning of the ways 14 and 16 in the clamp plates 3 and 4. Thus, the overall width and the overall length of the sole portion of the anti-slipping device may be adjusted according to the shape and size of a shoe sole provided therewith. Furthermore, by such longitudinal or transversal adjustment of the clamp plates 3 and 4 with relation to the sole body 1, it will be readily understood and appreciated that the downwardly extended tapered or sharpened portions of the calks may be selectively positioned whereby to provide the greatest possible comfort and/or anti-slipping efficiency to the device when adapted to a wearer's street or casual wear shoe. This latter is of material importance and the relative adjustment or positioning of the calks will, of course, vary according to the stance of the wearer.

Bolt calks, as hereinbefore described, are also downwardly engaged through the obliquely disposed pairs of ways 12 and 12' in the outward or rearward portion of the heel body 2. The positions or relationing of these latter bolt calks may be readily adjusted or varied with relation to said heel body by loosening their respective clamping nuts 21 and shifting or sliding the same in their individual ways 12 and/or 12'—then, tightening the clamping nuts 21, as hereinbefore described.

To apply or adapt my improved anti-slipping device to the normal street wear or casual shoe of a wearer or user, the sole portion of such shoe, subsequently to the hereinbefore described adjusted assembly of the anti-slipping device, is slid longitudinally forwardly of the device so that the opposite sides of its sole are engaged over by the relatively opposed jaws 13 and 15 on the outer sides of the clamp plates 3 and 4. The heel of the shoe is now engaged in and directly adjacent the counter portion 7 of the heel body 2, whereupon the securing strap 10', engaged with the counter 7, is passed over the user's ankle and fastened or secured, as by the illustrated buckle or such other separable fastening device as may be provided to the strap.

Attached as above described, the improved anti-slipping device will convert the normal street or casual wear shoe into a sport shoe quite satisfactory and efficient for the playing of golf or participation in various other sports requiring the use of spiked or calk shoe treads.

Because of the mode of attachment of the anti-slipping device to a shoe, it can be conveniently and quickly removed therefrom, thus returning the shoe to its normal or ordinary condition, all without damaging or injuring the same in any manner.

While I have hereinbefore disclosed the invention as being equipped with the heel counter 7 and attaching strap 10', it will be understood that other and different forms of attaching means may be substituted therefor, such as conditions or preference may dictate.

I claim:

1. In combination, a shoe tread member comprising relatively adjustable heel and sole bodies, the sole body having a plurality of generally transversely disposed ways therein, a plurality of clamp plates flatly adjacent portions of one side of said sole body, each of said plates having a plurality of generally longitudinally disposed ways therein in a manner to and being of a number to individually intersect the ways in the sole body, said heel body having a plurality of relatively angularly disposed ways formed therein, a plurality of calks equaling the number of ways in said sole body, heel body and plates, means on said calks engaged through the sole body and plate intersecting ways and through the ways in said heel body mounting the calks on the heel body and on the sole body and plates and interconnecting said plates to said sole body, and means on the heel body and clamp plates for connecting the same to a shoe and over the tread portion thereof.

2. In combination, a shoe tread engaging body having a plurality of generally transversely disposed and individual ways therein, a plurality of plates flatly adjacent portions of one side of said body and in transversely opposed relation, each of said plates having a plurality of generally longitudinally disposed ways therein in a manner to and being of a number to individually intersect the ways in the sole body, shoe sole engaging and clamp jaws carried on the outer side portions of said plates overlapping adjacent side portions of the shoe sole body, a plurality of calks equaling the number of ways in said sole body and plates, and means on said calks engaged through the sole body and plate intersecting ways mounting the calks on the body and plates and interconnecting said plates to said body.

3. In combination, a shoe tread member comprising relatively laterally and longitudinally adjustably interengaged heel and sole bodies, the sole body having a plurality of generally transversely disposed ways therein, a plurality of plates flatly adjacent portions of one side of the sole body in substantially transversely opposed relation, shoe sole engaging clamp jaws on outer side portions of each of said plates overlapping adjacent side portions of the sole body, each of said plates having a plurality of generally longitudinally disposed ways therein in a manner to and being of a number to individually intersect the ways in the sole body, said heel body having a plurality of relatively spaced and angularly disposed ways therein, a plurality of calks equaling the number of ways in said heel and sole bodies, and means on said calks engaged through the intersecting ways in said sole body and plates and through the ways in said heel body mounting the calks thereon and adjustably interconnecting said sole body and plates.

LEO V. RUSSO.
